UNITED STATES PATENT OFFICE.

HENRY W. UHL, OF FREEPORT, NEW YORK.

STARTING AND LIGHTING SYSTEM.

Specification of Letters Patent. Patented Apr. 18, 1916.

1,179,779.

Application filed November 10, 1914. Serial No. 871,219.

To all whom it may concern:

Be it known that I, HENRY W. UHL, a citizen of the United States, residing at Freeport, county of Nassau, and State of New York, have invented certain new and useful Improvements in Starting and Lighting Systems, of which the following is a specification.

My invention relates to improvements in starting and lighting systems as applied particularly to automobiles. Unitary systems or apparatus are in use in which an electric motor may be operated for starting an automobile engine, and used as a dynamo when the engine is in operation for operating the lighting system of the vehicle and charging batteries. In such devices, if directly connected to the engine fly-wheel or other rotatable part of the engine to start the same, a considerable amount of torque must be developed at the outset to overcome the inertia of the movable parts of the engine so that in such systems a motor of considerable power is required. In such systems also when the apparatus is used as a dynamo for lighting and other purposes, difficulties are experienced in regulating the voltage supplied to the lamps, under the conditions of varying speed of the engine and of the dynamo driven thereby.

My invention is directed to the provision of an improved method and of apparatus by which such method may be practised for overcoming these and similar difficulties in a simple and highly effective manner.

In my invention, when the electrical devices are supplied with current and used as a motor for starting the engine, a novel method and means are provided for permitting the motor to attain a considerable speed before any turning effect is applied thereby to the engine so that a smaller or less powerful motor can be used than is the case when a motor of usual construction is directly connected to the engine, no mechanical clutching devices being necessary in my construction between the engine and motor. When apparatus used in my method is employed for furnishing current to lighting systems, etc., an automatic control is provided which regulates the electrical output at all speeds of the vehicle so that a predetermined voltage will not be exceeded.

The arrangement is such that when there is no current in the external circuit of the apparatus, there will be no cutting of mag-

netic lines and no current generated by the dynamo. The arrangement also is such that when the engine of the vehicle increases its speed, the speed of one element of the dynamo, such as the armature, relative to or past the other element, or field, does not correspondingly increase, the relative movement between the armature and field, as distinguished from the absolute movement of either of these parts, being regulated automatically, so that there may be as many, or more, magnetic lines cut by the armature when the vehicle engine is running at slow speed, or is idling, than when the engine is running at high speed. These effects are obtained by my invention by the employment of a motor or dynamo apparatus in which both the armature and field magnet structure are freely revolved under certain conditions and one or the other is held or retarded in its rotation under other conditions. When the device is used as a motor, current supplied to the windings thereof causes one of its rotatable elements, as the armature, to start and get up speed, the other element, as the field magnet structure, referred to hereinafter briefly as the "field," being rotated in the opposite direction because of connections between the two. After this, braking means are applied to retard and stop the rotation of one of these elements, as the field, the rotation of the other element, the armature, for example, continuing, turning effect upon the shaft connected with the vehicle engine being applied as the held part slows down, the latter then forming an abutment about which the connections, referred to, between the field and armature, revolve, the rotation of these connections serving to turn over the engine. As a result of this arrangement, turning effect upon the engine will be applied gradually, increasing as the held part slows down, and reaching a maximum when it becomes stationary.

When the system is used for supplying current to the lighting system or for other purposes, means and a method are provided for regulating the relative movement of the field and the armature, one of these elements being held when the engine is rotating at low speed and permitted movement in the same direction as the other element when the engine speed is increased, the movement of the held element increasing as the speed of the engine increases so that the speed of ro-

tation of the armature relative to the field is constantly adjusted in accordance with the variation in speed of the engine to furnish current of approximately constant voltage.

5 While these ends may be attained by various means and with modifications in details of the method practised, the principle of operation will remain the same.

In order that a clearer understanding of 10 my invention may be had, attention is hereby directed to the accompanying drawings forming part of this application and illustrating one form of apparatus, which I consider well adapted for my purpose and by 15 which my improved method may be carried out.

In the drawings Figure 1 represents a vertical longitudinal section through apparatus which operates as a motor for starting 20 and as a dynamo when the engine is in operation and it is desired to provide current for lighting, etc., Fig. 2 represents a transverse vertical section taken on line 2—2 of Fig. 1, Fig. 3 is a transverse section taken 25 on line 3—3 of Fig. 1, Fig. 4 is a diagrammatic representation of wiring connections, Fig. 5 is a diagrammatic detail view illustrating means for starting the motor and subsequently applying a brake to the field 30 casting, and Fig. 6 is an end view showing the machine connected to the fly-wheel of an engine.

Referring to the drawings in my preferred 35 form of construction, a shaft 1 is provided carrying at its end the pinion 2 adapted to mesh with a gear on the fly-wheel or other rotatable part of the engine to drive the same when the machine operates as a motor and to receive power therefrom when 40 the machine operates as a dynamo. A tubular armature shaft 3 surrounds shaft 1 and carries thereon the armature 4 which is preferably shunt wound, in respect to the field winding, although other forms of winding 45 may be used. The field 5 is mounted for rotation around the armature. A brake band 6 is shown applied to the surface of the field 5, being mounted within a depression 6' in the casing 8. A bearing is provided for shaft 1, as shown at 7, adjacent to pinion 2 in a hub formed on the casing 8, which latter preferably is semi-cylindrical and surrounds and protects the lower half 50 of the apparatus. The opposite end of shaft 1 may be given a bearing as illustrated at 9 within the tubular armature shaft. The armature shaft is supported adjacent the end just referred to in a bearing 10 formed in a hub 11 of the casing or supporting member 8. The field member 5 is mounted to rotate 55 about the armature shaft by means of castings or suitable frames 12 and 13 at each end of the field member to which the field member is secured as by screws or bolts 14. Members 12 and 13 have hub portions 15, 15

which are rotatably supported by suitable bearings upon armature shaft 3.

A gear 16 is secured to the left hand end 70 of armature shaft 3, referring to Fig. 1, by a key or other suitable means, and a spider 17 is secured to shaft 1 adjacent to the gear 16. The spider 17 has a number of arms, for example three, extending radially from its hub 18 at the end of each of which is mounted a stud 19 extending parallel to 75 the armature shaft. On these studs, pinions 20 are mounted to freely rotate about the studs, pinions 20 meshing with gear 16. An internal gear 21 is mounted for engagement with pinions 20 at the outer periphery 80 of the latter. Internal gear 21 is provided with a radial outwardly extending annular flange 22 which contacts the surface of a flange 23 formed on member 13, to which flange 22 is secured. A member 24, of cylindrical form has a hub 25 which is mounted for rotation on a suitable bearing 26 on shaft 1 adjacent to the bearing 7 of the shaft. Member 24 has an annular flange 27 upon which the outer edge of internal gear 90 21 rests, bolts 28 extending through member 24, the flange 22 of gear 21 and into boss 23 of member 13, thus rigidly connecting gear 21 to the field member 5, since the latter also is rigidly secured to member 13. 95 It may be remarked, circular members 13 and 24, together with the inner surface of gear 21 form a closed chamber which may be partly filled with oil if desired to form a reservoir from which the various bearings 100 may be lubricated. As shown, the machine has four brushes 29 which bear at intervals of ninety degrees upon the commutator 30, the two positive brushes contacting with collector ring 31, with which contact 32 engages, the latter being connected to the binding post 33. The two negative brushes are 105 preferably grounded.

Any suitable means may be provided to 110 operate the brake-band 6, when the field 5 is to be stopped or retarded in the operation of the device as a motor for starting the engine. A suitable arrangement is illustrated diagrammatically in Fig. 5, in which a foot-lever 34 is connected by means of bell-crank 35, link 36 and lever 37 with one end of the brake-band 6, and through levers 37 and 38 with the other end of the brake-band, so that depression of the foot-lever 115 results in tightening the band and retarding and stopping the field 5. This foot-lever may be employed to close a switch to close the circuit for supplying current to the motor and starting the same in operation before the brake is applied, since it is only 120 necessary for the armature to revolve for a brief period before the break may be applied thereto. The starting switch referred to is illustrated at 39, 40, the two members of which may have connections 41, 42 con- 125 130

nected thereto leading to the battery or source of power by which the machine is energized when it is operated as a motor. In order to insure the foot-lever being applied with sufficient slowness to enable the armature to get up speed before the brake is applied, I prefer to employ a dash-pot or similar retarding device 43 into which the end of foot-lever 34 extends on the depression of the same.

From the above, the operation of the device as a motor for starting the engine may be made clear. When current is supplied to the apparatus, the armature immediately starts revolving, gear 16 thereon rotates pinions 20 about their own axes and the latter rotate gear 21 and therefore also the field 5 in the opposite direction of rotation to that of the armature 4. The inertia of the moving parts of the engine to which shaft 1 and spider 17 are connected will prevent rotation of spider 17 and pinions 20 about the axis of shaft 1 at this time. Pinions 20 revolve gear 21 at the same angular velocity as gear 16, but since gear 21 is larger and has a greater number of teeth than gear 16, the field will rotate a less number of revolutions per second than the armature and in the opposite direction thereto. In order now to obtain a rotative effect upon the shaft 1, it is only necessary to hold either the field or the armature against rotation or to retard the rotation thereof, whereupon the pinions 20, meshing with both gears 16 and internal gear 21 will necessarily start rotation about shaft 1, rotating the same with them. The shaft 1 will be rotated in the same direction, which is the proper direction for starting the engine, if either the field or the armature is stopped or retarded regardless of which one is stopped, if proper winding of the field is used. In the construction illustrated, the field being considered as shunt-wound, I apply a brake-member to the field as stated to retard and stop the same. The brake member might have been applied to the armature shaft, instead of the field, but in that case a different form of winding would be employed for the field, than that referred to above, preferably a series winding, to obtain rotation of the engine in the desired direction for starting. In principle, it is only necessary to slow down and stop one of these elements while permitting the other to revolve, the element slowed down and stopped acting as an abutment, that is, either the gear 16 or the gear 21 acting as an abutment about or within which the pinions 20 and spider 17 start revolving about the axis of the spider to rotate shaft 1, and the power is applied gradually to shaft 1, since the tendency of spider 17 to revolve increases in proportion as the part which is held slows down.

Considering now the operation of the same, when the armature and field are operated so as to constitute the source of electrical energy for supplying the lighting system, etc., the gear 2 on shaft 1 being connected and driven from the engine fly-wheel, spider 17 revolves about its axis and pinions 20 thereon would revolve gears 16 and 21 together, that is, in the same direction if the armature and field were equally free to rotate, since in this case there would be nothing to cause pinions 20 to rotate about their own axes. In this case, pinions 20 would act simply as devices for connecting gears 16 and 21 together and these gears, and the armature and field, would rotate together in the same direction at the same number of revolutions per second, so that there would be no magnetic lines cut by the armature and no current generated. This is practically the case, as will be pointed out, when there is no current in the external circuit of the machine, as when it is not desired to operate lights, and the appropriate switch in the external circuit is open. In order for current to be generated, either the armature or the field must be held stationary or retarded in its movement so that there is relative movement between the two resulting in the cutting of magnetic lines.

As stated, my invention provides controlling means, such that one of these elements is held stationary or approximately so when the engine is running at slow speed and is permitted a movement of increasing speed in the same direction as the other element, as the engine increases in speed, so that the voltage supplied as the engine speed increases, will not increase above a predetermined desired amount but will remain approximately constant. When the field, for example, is held against rotation pinions 20 will revolve about their own-axes, in addition to rotating with spider 17 about the axis of shaft 1 and the relative movement between the armature and field is provided.

Various means are possible whereby one of the elements of the dynamo may be held or retarded in its rotation in the described manner. I prefer to use the method which I will now describe and which I consider well adapted for the purpose. This comprises an electro-magnetic controlling device similar to an induction motor having a squirrel cage armature, which is mounted about the internal gear 21. The stator of this device is represented at 44, this comprising a ring winding, which is connected in series with the circuit from the armature 4. The stator is held stationary as by means of bolts 45 securing the same to a lug or lugs 46 on the interior of the casing 8. This stator is so wound as to produce alternating north and south poles, the same as in an alternating current squirrel cage motor, there

being, for example, eight poles provided. The rotor 47 comprises a plurality of short-circuited iron bars, the same as in the usual squirrel cage motor. The elements of the 5 rotor 47 are connected rigidly to the field 5 by any suitable means, such as the bolts 28, which in the construction illustrated not only secure gear 21 to the revoluble frame member 13 and the field 5, but also secure 10 the rotor to the member 13. With this construction, when the engine is revolving at slow speed, if the external circuit through the stator 44 is closed, the influence of the stator upon the rotor holds the latter 15 against rotation and the revolution of the armature within the field supplies current of desired voltage to the external circuit. This is because the torque exerted by the stator upon the rotor will be greater under 20 these conditions than that exerted by the armature upon the field, because the radius of the stator is greater than that of the field, as illustrated, and because the iron of the stator and rotor will have more residual 25 magnetism than that of the armature and field, because of the flux-density of the stator having been carried to an excessively high degree, and also for the reason that the rotor conductors are short-circuited while 30 the armature wires are not. As, however, the speed of the engine shaft is increased, the permeability of the iron of the stator decreases and there is an increasing magnetic leakage from the stator because of the 35 cross-section of the stator and rotor being intentionally made of small area. The cross-sections of the stator and rotor are so chosen that when the engine is running slowly, the permeability of the iron in the 40 stator and rotor is practically the same as that of the iron in the field and armature of the dynamo, but as the desired voltage for the external circuit is approached, the iron of the stator and rotor approaches magnetic 45 saturation. The stator and rotor being nearer the saturation point than the armature and field of the dynamo, an increase of the current generated by the machine traversing the stator windings results 50 in only a small increase in the magnetism of the stator as compared with that of the dynamo, as a result of which a point is reached at a predetermined voltage of output when the torque of the dynamo is greater than 55 that of the controlling device so that the rotor begins to slip and rotates slowly, together with the field in the same direction as the armature. As the speed of the engine increases, the slip of the rotor increases, 60 so that the voltage of the external circuit is automatically regulated as described.

The electrical connections described are illustrated diagrammatically in Fig. 4. When the device is operated as a motor for 65 starting the engine, the switch 48 in the

external circuit is open, and the switch 39, 40 being closed, current is supplied from any suitable source, such as the storage battery 49, to the armature. When it is desired to supply current for the lights 50 or 70 for other purposes, the armature 4 being rotated from shaft 1 through pinions 20 and gears 16 as described, the switch 39, 40 is open and switch 48 is closed, the current generated by the machine passing through 75 the stator windings and supplying the lights, charging battery, etc., as desired. In Fig. 1 the conductor 51 is illustrated as connecting the armature with the stator windings, current being led from the stator 80 windings to the external circuit through a connection at binding-post 52. When the device is operated as a motor, the stator is not included in the circuit.

In practice, the storage or charging battery 49, to be supplied with current, would be connected in parallel with the lamps 50, an auxiliary switch 48' being diagrammatically illustrated in Fig. 4 in this connection, switch 48 being closed when current is to 90 be supplied to the lights, and switch 48' closed when it is to be supplied to the battery. As stated, the armature 4 is preferably provided with four poles and is shunt-wound, two of the poles being grounded, as 95 is diagrammatically illustrated in Fig. 4.

The top of the machine may be covered by a light cover 53, which may be secured to the bottom casting 8 in any desired manner, as, for example, by a hinge connection 54 or the 100 like at one side and a spring clip or other suitable retaining device 55 at the other side of the machine, as illustrated in Fig. 2. In Fig. 6, the gear 56 on the fly-wheel of an engine to be started, when the machine is 105 operated as a motor, or to supply turning power to shaft 1 when the machine operates as a dynamo, is illustrated as in mesh with gear 2 on shaft 1.

From the above, the manner of practising 110 the methods which I have referred to as comprising a part of my invention will be manifest. Generally speaking, my method of starting a motor or of applying torque to a rotatable member having considerable inertia, which is to be started from rest, consists in rotating both the armature and field of a motor in opposite directions, and in such a manner that a part of each of the same will rotate at the same angular speed. 115 After the rotatable elements have gotten up speed, one or the other of the same is retarded and the relative change in the rates of rotation of the field and armature is utilized for gradually applying torque to 120 the shaft or member to be turned over. My method in connection with furnishing current of approximately constant voltage or current which shall not exceed in voltage a predetermined amount, regardless of the 130

variations in speed of the engine operating the dynamo, consists in employing an armature and field both of which are rotatable, driving one of the same, and regulating the amount of slip of the other rotatable member of the dynamo in such a manner that the speed of the armature relative to and within the field shall always, within certain limits, be approximately the same or at any rate shall not exceed a certain predetermined amount. While the methods briefly described are efficiently carried out by means of the apparatus described, the same may be practised by other means than those described.

15 It is to be understood that my invention is not strictly limited to the exact details of construction described in connection with my apparatus, but that my invention, both 20 as to apparatus and method, is as broad as is indicated by the appended claims.

25 Having now particularly described my invention, what I claim and desire to protect by Letters Patent is as follows:—

1. In devices of the character described, 30 the combination of a pair of rotatable elements, namely, a rotatable armature, and a rotatable field, a shaft adapted to be connected to an engine to be started, connecting means for causing the armature and field to rotate in opposite directions when current is supplied to the armature, brake means for retarding and stopping the rotation of one of the said elements, when desired, and a 35 member connected to said shaft, and so connected to said connecting means as to have rotative effect applied thereto by said connecting means when said brake means is applied, but not otherwise, substantially as set forth.

40 2. In devices of the character described, the combination of a dynamo or motor comprising a pair of rotatable elements, namely, an armature and a field, a shaft adapted to have mechanical power taken therefrom, when said elements operate as a motor, and to have mechanical power supplied thereto, when said elements operate as a dynamo, means for retarding at will the rotation of one of said elements, when operating as a 45 motor, means for automatically retarding one of said elements, when operating as a dynamo, and connections between said shaft and said elements such that said elements 50 operate in opposite directions and rotative effect is applied to said shaft from the unretarded element when the latter operates as a motor, and said elements rotate in the same direction at different speeds, and rotative effect is applied from said shaft to the 55 element which is not retarded, when the latter operates as a dynamo, substantially as set forth.

60 3. In devices of the character described, 65 the combination of a dynamo comprising a

pair of rotatable elements, namely, an armature and a field, a shaft adapted to be connected to an engine of variable speed, means for positively rotating both said elements together in the same direction from said shaft when neither element is held or retarded, and for rotating either when the other is held or retarded, and means tending to hold one of said elements with an effectiveness which automatically decreases as the speed of said shaft increases, substantially as set forth.

4. In devices of the character described, the combination of a dynamo comprising a 70 pair of rotatable elements, namely, an armature and a field, a shaft adapted to be connected to an engine of variable speed, means connected with both said elements for rotating said elements together from said shaft when neither element is held or retarded, 75 and for rotating either when the other is held or retarded, an external circuit, and devices actuated by current in said circuit, when the latter is connected to said dynamo as a source, tending to hold one of said elements 80 with an effectiveness which decreases as the speed of said shaft increases, substantially as set forth.

5. In devices of the character described, the combination of a dynamo comprising a 95 pair of rotatable elements, namely, an armature and a field, a shaft adapted to be connected to an engine of variable speed, an external circuit, adapted to be connected to said dynamo as a source, means for rotating 100 one of said elements from said shaft, and means actuated by current in said circuit, when the latter is connected to said dynamo as a source, for holding said other element against rotation so long as the speed of said 105 shaft does not exceed a predetermined rate, and thereafter permitting slip of said other element, substantially as set forth.

6. In devices of the character described, the combination of a dynamo comprising a 110 rotatable field and a rotatable armature, an immovable coil, wound to produce alternating north and south poles, in series with said armature, a rotatable magnetizable member in inductive relation to said coil, 115 and secured to said field, an external circuit in series with said coil, and means for rotating said armature, substantially as set forth.

7. In devices of the character described, 120 the combination of a dynamo comprising a rotatable field and a rotatable armature, an immovable coil, wound to produce alternating north and south poles, in series with one 125 of said dynamo elements, a rotatable short-circuited member in inductive relation to said coil, and secured to said other element, an external circuit in series with said coil, and means for rotating said first element, 130 substantially as set forth.

8. In devices of the character described, the combination of a dynamo comprising a rotatable field and a rotatable armature, an immovable stator element, wound as a ring with alternating opposite polarities around the same, in series with one of said dynamo elements, a rotor element of squirrel-cage type, in inductive relation to said stator element, and secured to the other of said dynamo elements, an external circuit in series with said stator element, and means for rotating said first-named dynamo element, substantially as set forth.
9. In devices of the character described, the combination of a dynamo comprising a pair of rotatable elements, namely, an armature and a field, a shaft adapted to be connected to an engine of variable speed, means for driving one of said elements therefrom, and an electric brake device comprising a part in circuit with one of said dynamo elements and a part connected to rotate with the other dynamo element, said devices being arranged to exert a greater torque between its elements at certain predetermined speeds of said shaft than is exerted between said dynamo elements at such speeds, and to exert a less torque at greater speeds of said shaft, substantially as set forth.
10. In devices of the character described, the combination of a pair of rotatable elements, comprising a rotatable armature and a rotatable field, a gear rotatable with the armature, an internal gear surrounding said
- first gear and rotatable with the field, a shaft to be driven coaxial with the armature, a spider secured thereto having radial arms and pins on said arms extending between the faces of said gears, pinions freely rotatable on said pins and meshing with both gears, and means for retarding and holding one of said rotatable elements against rotation, substantially as set forth.
11. In devices of the character described, the combination of a pair of rotatable elements, comprising a rotatable armature and a rotatable field, a gear rotatable with the armature, an internal gear surrounding said first gear and rotatable with the field, a shaft to be driven coaxial with the armature, a member secured thereto having a pin extending between the faces of said gears, a pinion freely rotatable on said pin and meshing with both gears, and means comprising a lever, a switch, a brake-band, and connections for successively operating said switch and brake-band, from a single point of control for supplying current to said armature, when it is desired to operate the same as a motor, and for braking the rotation of said field after said armature has gotten up speed, substantially as set forth.

This specification signed and witnessed this 4th day of November, 1914.
